UNITED STATES PATENT OFFICE.

WILLIAM HOUGHTALING, OF BRIDGEPORT, CONNECTICUT, ASSIGNOR TO
EDWARD S. T. KENNEDY, OF NEW YORK, N. Y.

PERFORATED PLATE FOR DRYING STEAM.

SPECIFICATION forming part of Letters Patent No. 389,078, dated September 4, 1888.

Application filed June 16, 1888. Serial No. 277,290. (No model.)

To all whom it may concern:

Be it known that I, WILLIAM HOUGHTALING, a citizen of the United States, residing at Bridgeport, in the county of Fairfield and 5 State of Connecticut, have invented certain new and useful Improvements in Perforated Plates for Drying Steam; and I do hereby declare the following to be a full, clear, and exact description of the invention, such as will 10 enable others skilled in the art to which it app pertains to make and use the same.

This invention relates to the drying-tubes of steam-boilers, and more particularly to perforated plates applied to the drying-pipes and 15 steam-tubes of radial-tube ("porcupine") steam-boilers for facilitating the drying of steam within the boiler and preventing any tendency to priming.

The object of the invention is to provide for 20 supporting the steam-drying pipes centrally in the radial steam-tubes of the boiler; also, to provide increased steaming capacity in a boiler of given size, by enabling the operator to raise the water-line, and thus utilizing a greater 25 number of radial tubes—the lower steam-tubes—for water, thereby protecting such tubes from overheating, due to overfiring; and a further object is to produce drier steam than heretofore, and to prevent any tendency in 30 this class of boiler to prime, which might result from overworking and abuse.

In carrying out my invention I apply perforated plates, each having suitable supporting-lugs and a boss, to the mouths of the steam-tubes, and particularly to those steam-tubes 35 into which extend the steam-drying pipes, in which case the perforated plates are slipped over the drying-pipes, and by their inwardly-extending lugs are thrust into the mouths of 40 the radial steam-tubes, all as more fully described with reference to the accompanying drawings, in which—

Figure 1 represents a vertical section of the upper portion of a radial-tube steam-boiler 45 with the furnace-shell removed, and showing the perforated plates applied to the upper steam-tubes. Fig. 2 represents an inner face view of a perforated plate on enlarged scale. Fig. 3 represents a vertical section through 50 the same.

The stand-pipe A is provided with the closely-set radial steam and water tubes a a', in the usual manner, and the usual steam-discharge pipe, B, extending with a closed lower end down into the stand-pipe, is provided with 55 the steam-drying pipes b, extending with open outer ends into the larger steam tubes, a. These drying-pipes b are preferably made in two parts, united by a coupling for convenience in connecting and removing them from the boiler. 60 The perforated plates or disks C are usually applied by slipping them over the drying-pipes b and securing them thereto by a set-screw in such position that they will cover the mouths of the steam-tubes a. The plates or 65 disks C have cast upon their inner faces, a short distance from their peripheral edges, three lugs, f, having straight outer edges in proper position to fit snugly inside of the steam-tubes a. A double row of perforations, e, 70 is formed in the disks, and they are preferably made flaring from the outer to the inner face of the disk. A central boss or collar, d, is cast upon the outer face of the disk, and has an opening, e, extending through it and the disk 75 for receiving the steam-pipe b. A set-screw, h, is applied to a screw-threaded hole in the boss for securing the disk to pipe b.

The perforated disks having the large central opening in the boss closed may be applied 80 to the mouths of steam-tubes a below those which contain the drying-pipes, so as to spray any water which may be thrown up into such tubes; but I have found the perforated disks most useful and advantageous when applied to 85 the steam-tubes containing the drying-pipes.

When inserting the drying-pipes b in the radial steam-tubes a, the perforated disks are slipped over such pipes, and are then applied to the mouths of tubes a so that their lugs f 90 fit snugly inside thereof, and the set-screw is then turned to hold the disk in place. In this position the disks hold pipes b exactly in the center of tubes a, and thus cause a better flow of steam. Pipe b, by being held at its open 95 end off from the bottom of tube a, would not readily receive any water which might be thrown into tube a, while if the pipe sagged any water in the tube would enter the pipe and be blown by the steam through it into 100

steam-outlet pipe B. The perforated plates also serve to a great extent to prevent water from entering the tubes *a*, to which they are applied, since water thrown against the plates 5 is broken into spray, and to a limited extent might enter the tube in that form, where it would be quickly converted into dry steam. The perforated plates, however, act to permit the passage of steam to the exclusion of water, 10 so that steam only is passed off in a very dry condition. On account of the efficient action of the perforated plates the water-line can be raised in the boiler from six to twelve inches above that ordinarily carried and still make 15 dry steam, thus increasing the steaming capacity of the boiler. Independent of the consideration of raising the water-line, however, improved results are secured.

The area of all the openings in all the perforated plates in any-sized boiler is varied 20 with the requirements of the case, and may be more or less than the area of the steam-pipe leading from the boiler.

Having described my invention, what I 25 claim, and desire to secure by Letters Patent, is—

1. In a radial-tube steam-boiler, the combination, with a steam-drying tube extending into the fire-box, of a removable perforated

plate applied to the tube for spraying any water which may be thrown against the mouth of the tube, and thereby producing dry steam. 30

2. In combination with the steam-tube of a boiler and its internal drying-pipe, a perforated plate applied to the mouth of the tube 35 and supporting centrally the internal pipe, for the purpose described.

3. In combination with the steam tube of a boiler, a perforated plate provided with inwardly-projecting lugs for supporting it in 40 the mouth of the tube, as described.

4. In combination with a steam-tube and its internal pipe, a perforated plate having inwardly-projecting lugs to support it in the tube and a large central opening for the passage of the internal pipe, as described. 45

5. In combination with a steam-tube and its internal pipe, a perforated plate having inwardly-projecting lugs, a boss or collar provided with a large opening, and means for securing the collar to the internal pipe, all for 50 the purpose described.

In testimony whereof I affix my signature in presence of two witnesses.

WILLIAM HOUGHTALING.
